JEWELRY BOX

Frank M. Bedinger, Chicago, Ill., assignor to F. H. Noble & Company, Chicago, Ill., a corporation of Illinois

Application July 8, 1952, Serial No. 20,518

Term of patent 3½ years

(Cl. D80—5)

To all whom it may concern:

Be it known that I, Frank M. Bedinger, a citizen of the United States, residing at Chicago, in the county of Cook, State of Illinois, have invented a new, original, and ornamental Design for a Jewelry Box, of which the following is a specification, reference being had to the accompanying drawing, forming a part thereof, wherein:

Figure 1 is a perspective view of a jewelry box, in closed position, showing my new design;

I claim:

The ornamental design for a jewelry box, substantially as shown.

FRANK M. BEDINGER.
